UNITED STATES PATENT OFFICE.

WILLIAM O. WEBBER, OF BOSTON, MASSACHUSETTS, ASSIGNOR TO LAWRENCE MACHINE COMPANY, OF LAWRENCE, MASSACHUSETTS.

COMPOUND CENTRIFUGAL PUMP.

No. 837,988.

Specification of Letters Patent.

Patented Dec. 11, 1906.

Application filed December 31, 1903. Serial No. 187,389.

To all whom it may concern:

Be it known that I, WILLIAM OLIVER WEBBER, a citizen of the United States, and a resident of the city of Boston, in the county of Suffolk and State of Massachusetts, have invented certain new and useful Improvements in Compound Centrifugal Pumps; and I hereby declare that the following is a clear, full, and exact description of the same, reference being had to the accompanying drawings, forming a part of this specification, in which similar characters represent the corresponding parts in all the views.

This invention relates to that class of centrifugal pumps in which the discharge from one pump is connected to the inlet of a second pump, and so on by successive stages through any number of pumps that may be desired, and has for its object the arrangement of such pumps so that the end thrust upon their disks or runners may result in counterbalancing or neutralizing the thrust upon them as a whole, this being of prime importance when pumping under the high heads for which this class of pump is primarily designed.

In Figure 1 a half vertical section is shown of a four-stage pump above the horizontal center line of the shaft and a half side elevation below said center line. Fig. 2 shows a half vertical section of same pump on the line X Y of Fig. 1 above the center line and a half end elevation below the center line.

A is a cylindrical outer casing of a pump provided with the water-passages a a^2 a^3 a^4 and discharge-outlet a^5 . This cylindrical casing is closed at one end by the inlet-head B, which is bolted to the cylindrical outer casing A by the bolts b. This inlet-head has an inlet passage-way b' and is provided with a stuffing-box b^6 , which may be of any suitable construction. The opposite end of the main casing is closed by the head C, which is secured to the main casing A by the bolts c and is provided with a cap c', integral therewith, which covers the end of the shaft D, also with a water-passage c''. At or near the middle of the axial length of the main casing A is introduced an annular recess-ring E, which is fixedly held in the cylindrical casing A. Adjacent to this annular ring E on one side is the fourth or discharging disk of the pump F, which is of the inclosed type and whose water-passage f discharges through

the whirlpool-space f' into the annular outlet-chamber a^4 . Next adjacent to the fourth disk is another annular section G, provided with a water-passage-way g. This annular section is also fixedly held in the outer casing A. Next adjacent to this section is the first inclosed disk or runner H, provided with a water-passage h. Next adjacent to the centrally-located annular section E on the opposite side from those just described is the third inclosed runner or disk I, provided with a water-passage i. Next adjoining this disk I is another annular section J, provided with a water-passage j. This section J is also fixedly held in the outer casing A. Next adjoining this section J is the second runner K, provided with a water-passage-way k. All of these disks or runners are tightly keyed to the shaft D and abut one against the other. A running fit is maintained between these disks and the annular interior sections wherever they come in contact, as shown in the drawings.

z z' z^2 z^3 are annular cored openings for the simple purpose of lightening the castings.

The action of this pump is as follows: The shaft D being set in revolution water enters the inlet passage-way b' , passes into the first disk H, and is thrown out through the passage-way h by the action of the blades of the disk L, which may be of any approved form. The water thus thrown from the first disk passes up through the passage-way a' in the outer casing A, in the direction shown by the arrows, enters the passage-way c' of the cover C, in which it is maintained at a certain pressure and velocity by the centrifugal action of the disk H. It is thus received under pressure and velocity by the second disk K, by which it is thrown in turn under still greater pressure and velocity into the annular passage-way a^2 , thence through the passage-way j to the third disk I, where it is still further accelerated, passing through the passage-way i of the disk I into the passage-way a^3 of the outer casing A, thence following the arrows through the passage-way g of the annular section G, under still greater pressure and velocity, into the fourth disk F, thence by the small passage-way f of this disk through the whirlpool-space f', and is finally delivered into the annular outlet-chamber a^4 under its maximum pressure and velocity, and is thence discharged through the delivery passage-way

^{a⁵} to the discharge-piping. By this combination the pump will be in complete balance and free from end thrust at all heights and velocities of discharges. To illustrate, assuming a pressure of twenty-five pounds on each successive disk, the first disk H would have a pressure of twenty-five pounds bearing upon the unbalanced portion thereof and forcing it toward the right hand, as shown in Fig. 1. The second disk K would be under a pressure of fifty pounds, forcing it in the same way toward the left. The third disk I would be under a pressure of seventy-five pounds, forcing it in the same manner toward the left. The fourth disk F would be under a pressure of one hundred pounds, forcing it in the same manner toward the right. Therefore there would be a thrust of twenty-five pounds on H and one hundred pounds on F to the right, a total of one hundred and twenty-five pounds, and a thrust of fifty pounds on K and seventy-five pounds on I to the left, making one hundred and twenty-five pounds, and the pressures would balance. While I have illustrated by the drawings a four-stage compound centrifugal pump, it is evident that this combination can be carried on indefinitely, and I do not wish to be limited to merely a four-stage pump, but to any combination having a plurality of disks. The arrangement of the impellers and connecting passages therein shown avoid short sharp water-passages between the impellers, which owing to the velocity of the liquid produces eddies and loss of power and provides passages with easy curves, which allow the liquid to change its velocity without friction or constraint. Furthermore, this structure equalizes the strain upon the casing and removes the heavy pressures from the stuffing-box ends of the pump and places it in the center, thus avoiding the inequality of strain upon the case and the heavy pressure upon the stuffing-boxes. By independently balancing the inlet and discharge pressures all thrust is obviated and the use of balancing-chambers is not necessary. This structure also prevents the variation in the lift of the first impeller from throwing the pump out of balance, as well as the mechanical variations in the pump-castings, which can only thus be adequately balanced.

Having fully described the construction and operation of this invention, what I desire to claim and secure by Letters Patent, is as follows:

1. In a compound centrifugal pump, a series of impellers constructed and arranged to discharge from the first into the last of the series, and from the last impeller into the next adjacent thereto.

2. In a compound centrifugal pump provided with a single-suction-inlet the construction and arrangement of the impellers, serially disposed, under the least pressure at the

opposite ends of the pump next adjacent to the stuffing-boxes and the impellers under greater pressure disposed intermediate of the end impellers.

3. In a compound centrifugal pump, a plurality of impellers, means for conveying the discharge from one outer impeller to the outer impeller at the opposite side of the pump, means for conveying the discharge from the last-mentioned impeller to the impeller next adjacent thereto and therefrom to an impeller intermediate of the first-mentioned impeller.

4. In a compound centrifugal pump, a plurality of oppositely-disposed impellers, those upon each side of the center of the pump disposed in the same direction, and means for conveying the discharge from one outer impeller to the outer impeller at the opposite side of the pump and thence to an intermediate impeller.

5. In a compound centrifugal pump, a series of impellers constructed and arranged to discharge from the first to the last impeller of the series, from the last impeller into the impeller next adjacent thereto, from this impeller into the impeller next adjacent to the first impeller of the series, and so on indefinitely, each two adjacently-connected impellers, after the first impeller, facing in the same direction and directly connected together by a passage-way at one side of the central discharging-impeller, the passage-way leading from the discharge of each pair of impellers so placed, connecting with a similarly-disposed pair of impellers, facing in the opposite direction, on the opposite side of the central impeller, the discharge from the last pair of impellers so placed, entering the central discharge-impeller on the side opposite to that of the entrance of the last pair of impellers, the discharge from the final centrally-disposed impeller directly connected with the vortex-chamber and discharge-opening of the pump.

6. In a compound centrifugal pump, a plurality of oppositely-disposed impellers arranged in two series, those in each series successively facing in one direction, a channel extending between the outer impeller of each series, and a discharge-passage communicating with an intermediate impeller of the series.

7. In a compound centrifugal pump, a series of impellers constructed and arranged to discharge from the first to the last impeller of the series, from the last impeller into the impeller next adjacent thereto, from this impeller into the impeller next adjacent to the first impeller of the series, and so on indefinitely, each two adjacently-connected impellers, after the first impeller, facing in the same direction and directly connected together by a passage-way at one side of the central discharging-impeller, the passage-

- way leading from the discharge of each pair of impellers so placed, connecting with a similarly-disposed pair of impellers, facing in the opposite direction, on the opposite side 5 of the central runner, the discharge from the last pair of impellers so placed, entering the central discharge-impeller from the opposite side to that of the last pair of impellers.
8. In a quadruple compound centrifugal pump, a plurality of impellers disposed in pairs facing in opposite directions and constructed and arranged whereby the first impeller discharges into the fourth impeller, the fourth impeller into the third impeller, and the third into the second impeller, serially disposed.
9. In a quadruple compound centrifugal pump the construction and arrangement of four impellers in pairs successively disposed 20 in opposite directions and operatively mounted on a shaft, a passage operatively connecting the first impeller with the fourth, a passage operatively connecting the fourth impeller with the third, a passage connecting 25 the third impeller with the second impeller, and a passage operatively connecting the second impeller with the pump-discharge serially disposed.
10. In a quadruple compound centrifugal pump, an outer envelop provided with water-passages, heads secured to the outer casing and forming bearings, a shaft journaled in said heads, impellers operatively mounted upon said shaft, partitions containing 30 water-passages fixedly held in said outer casing and alternately disposed in relation to the impellers, a passage operatively connecting the first with the fourth, a passage operatively connecting the fourth with the third, 35 a passage operatively connecting the third with the second, and a passage operatively
- connecting the second with the discharge, serially disposed, the first and second facing in one direction and the third and fourth facing in the opposite direction.
11. In a multistage centrifugal pump the combination with a casing containing a series of impeller-chambers in alinement, of a plurality of rotary impellers, each in one of 45 said chambers, and passages in the casing connecting the chambers for serial operation of the impellers, the chamber connected with the inlet being at one end of the series, and that connected with the outlet being an intermediate one of the series.
12. In a multistage centrifugal pump, the combination with a casing containing a series of impeller-chambers in alinement, of two or more pairs of rotary impellers each impeller in one of said chambers, a shaft 50 carrying said impellers, and passages in the casing connecting said chambers for serial operation of the impellers, said passages and impellers being so arranged that the impellers of each successive independent pair, in 55 the order of their operation, beginning with the first impeller, face in opposite directions, and the impellers of each successive independent pair beginning with the second impeller, face in the same direction, the chamber connected with the inlet being at one end 60 of the series of chambers in alinement, and that connected with the outlet being an intermediate one of the series.
- In testimony whereof I have hereunto affixed my signature in the presence of two 65 subscribing witnesses.
